PATIENT-CARRYING VEHICLE FOR
HOSPITALS

Richard M. West, Columbus, Ohio

Application June 26, 1952, Serial No. 295,758

2 Claims. (Cl. 5—81)

1

This invention relates to hospital appliances, having particular reference to an improved wheeled carrier vehicle adapted for the transfer of patients, while disposed in prone positions, between hospital beds and operating room tables, or on other analogous situations.

The ordinary wheeled carrier vehicles for hospital use, as the same are now generally constructed, provide a frame which is equipped at the top thereof with a stationary bed, the latter forming a fixed part of the frame on which patients are placed in prone positions for transference between one department of the hospital and another. Considerable difficulty is often encountered in the operation of such a conventional carrier in lifting, for instance, a patient upon whom a surgical operation has just been performed, and transferring the patient from the carrier vehicle and placing the patient on the mattress of a standard hospital bed. Often, the operation requires the combined services of two or more nurses or attendants in effecting such transfer, and accomplishing the same in a manner preventing or minimizing physical discomfort on the part of or injury to the patient.

Among others, therefore, the present invention has for certain of its objects: to provide a wheeled hospital carrier embodying a frame on which is mounted a laterally shiftable patient-receiving bed, and wherein the latter is so formed as to be capable of being projected laterally to one side or the other of the carrier vehicle in order that said bed may overlie the mattress of the associated hospital bed, so that a patient may be discharged from the carrier vehicle and deposited on the bed with but a minimum of help and with the positive assurance that the patient will not be dropped; to provide a shiftable bed for hospital carrier vehicles in which the bed is composed of a plurality of pivotally united longitudinally extending, parallel slat members, and wherein each of the slat members at the ends thereof is equipped with anti-friction devices or rollers which are movable in frame-carried guides, whereby to facilitate lateral shifting movement of the carrier bed on its supporting frame; to provide a hospital carrier of the type set forth in which the frame thereof is provided at its sides with hinged extension brackets, which normally extend parallel with the length of the carrier frame, but which are capable of assuming laterally disposed positions in which the brackets project perpendicularly from the sides of the carrier frame, the said brackets serving as supporting members for the laterally shiftable bed of the

2

carrier vehicle when said bed is moved outwardly from one side or the other of the carrier frame; to provide a construction of this character in which the extension brackets are formed with groove-like guides which are adapted to be brought into registry with corresponding guides provided in the transversely extending stationary end members of the carrier frame, the said guides receiving the antifriction devices or rollers formed on the ends of the slat members of the laterally shiftable carrier bed, whereby to provide full support for and to facilitate movement of said bed in all its operating positions; and, finally, to provide a hospital carrier which constitutes generally an improvement upon previous types of carriers heretofore employed in the capacity set forth.

These, and other objects and advantages of the invention, which will be obvious to those familiar with the art, are attained by means illustrated in the accompanying drawings, in which similar numerals refer to similar parts throughout the several views, as follows:

Fig. 1 is a perspective view of a hospital carrier vehicle formed in accordance with the present invention. In this figure, the vehicle has been illustrated as disposed adjacent to a mattressed hospital bed, and with the extension brackets of the carrier vehicle projected over the mattress of the hospital bed in obtaining extended lateral movement of the bed of the carrier vehicle.

Fig. 2 is a vertical transverse sectional view taken on the plane indicated by the line 2—2 of Fig. 1;

Fig. 3 is a similar view on an enlarged scale, disclosing the lateral shiftable bed of the carrier vehicle in an extreme position of lateral extension;

Fig. 4 is a vertical sectional view on the line 4—4 of Fig. 3;

Fig. 5 is a horizontal sectional view taken on the plane indicated by the line 5—5 of Fig. 3;

Fig. 6 is a detail perspective view of the slat-member carried rollers provided in connection with the shiftable bed construction of my improved carrier vehicle.

Referring more particularly to the drawings, there has been illustrated at 1 a hospital carrier vehicle in which is incorporated the mechanical features of the present invention. The carrier comprises a metallic frame 2 which, in this instance, is formed to comprise parallel, longitudinally extending, side rails 3. The latter are united at their ends by transversely disposed, stationary end members 4. Extending rigidly and

downwardly from the joined corners of the side rails 3 and the end members 4 are vertical tubular legs 5, the latter preferably having mounted on the lower ends thereof casters 6, equipped peripherally with resilient tires. The frame of the carrier is additionally reinforced by means of tubular braces 7, which are rigidly joined at their ends with the vertical legs 5. This construction produces a strong, lightweight and rigid frame structure, and one capable of being used advantageously in carrying out the present invention.

Mounted for movement laterally on the top of the frame structure is a carrier bed 8. Patients are adapted to be placed in a prone position on this bed for transportation from one department 15 of a hospital, for example, to another. In this instance, the bed 8 is formed to comprise a plurality of longitudinally extending parallel, closely related slat members 9. The opposite ends of each of these members are, in one form of my invention, connected with metallic plates 10, which are disposed preferably on the underside or surfaces of said slat members. In this instance, each plate is formed with a depending ear 11, which carries a stud 12 upon which is 25 journaled a roller 13. Also, said plates are hinged together in a manner flexibly uniting the slat members as at 11a. By reference to Figs. 2 and 3 of the drawings, particularly, it will be noted that the rollers are positioned in supporting and 30 guiding grooves 14, which extend lengthwise of the inner face of each of the channel members 4, and are disposed in a horizontal plane above that of top flanges of the side rails 3, as shown in Fig. 3.

In order to permit the bed 8 to be moved laterally beyond the longitudinal sides of the carrier frame, use is made of extensible and retractable frame-carried bed supports. As an example of such supports and in the drawings there is hinged as at 15 to the ends of the angle rails 3 extension brackets 16. As shown at the right of Fig. 1, these brackets are normally positioned to extend parallel or longitudinally with the rails 3, where they will be out of the way. However, when it is desired to move the bed 8 laterally to one side or the other of the frame 2, the brackets 16 on the side of the frame toward which the bed is to be moved are turned about their hinges so that said brackets extend at substantially right angles to the plane of the rail 3 to which they are attached. When in such extended positions the ends of the bed-supporting and guiding grooves 17 formed in the inner surfaces of the brackets are brought into registry with the complementary grooves 14 of the end frame members 4, so that the rollers 13 provided on the ends of the slat members of the bed 8 may be caused to travel in the grooves 17 in the same manner as they travel in the grooves 14, sustaining the weight of the bed 8 and that of an invalid or patient disposed thereon and facilitating movement thereof. It will be noted that the grooves 17 are, as shown in Fig. 3, substantially of U-shaped formation. By such formation the slat members of the bed 8 are enabled to turn around the outer ends of the brackets 16, while their spaced order is maintained. The longitudinal edges of the slat members are rounded as at 11a to avoid any possibility of pinching the patient between them if the same come together when in a horizontal plane.

By this construction one person may easily remove a patient from the table provided by the carrier without injury or discomfort to the pa-

tient. Thus, by locating the carrier as shown in Fig. 1, the bed thereof may be moved laterally in a manner which will cause the slat members to turn about the U-shaped outer ends of the guide grooves 17 of the brackets 16, thereby depositing the patient gently and without discomfort, or the expenditure of any considerable effort on the part of the attendant in making the transfer. Similar convenience is obtainable in transferring a patient from a hospital bed to the carrier bed as there is little or no lifting of the patient. It will be noted that the brackets 16 are provided on both sides of the frame 2, a feature of decided advantage in manipulating the carrier in crowded hospital rooms or wards, where restrictions imposed by closely positioned furniture prevent free manipulation of the carrier on a floor surface. Because of the rollerized support provided for the rigidly united slat members of the carrier bed, the latter shifts easily from one operating position to another with but slight expenditure of physical effort. It will be understood that the legs 5 may be telescopic to vary the height of the frame 2, as is well known in the art.

Certain substitutions of materials, part arrangement and variations in structural contour will be obvious to those skilled in the art and may be employed without exceeding the scope of the invention as described in the foregoing teachings, and in the appended claims.

I claim:

1. A portable carrier for transporting invalids and hospital patients, comprising: a rigid rectangular frame composed of spaced parallel longitudinally extending side members, transversely disposed end members rigidly united with the ends of said side members and vertically depending wheel-carrying legs rigidly joined at their upper ends with the corners of said frame, said end members being formed with guideways extending linearly thereof; horizontally disposed extension brackets hinged to the outer corner portions of said frame for swinging movement about vertical axes between retracted inactive positions in which said brackets extend parallel with and adjacent to said side members, and active extended positions in which the brackets project perpendicularly from said side members and in positions of registry with said end members to form continuations thereof, said brackets being formed with guideways which register with those of the end members when said brackets occupy their active positions of extension, the guideway of each bracket including upper and lower parallel portions which are joined at their outer ends by an arcuate semi-circular portion; a horizontally disposed patient-receiving bed composed of a plurality of parallel longitudinally extending slat members arranged in immediately adjacent order and coextensive with the length of said frame; connecting means hingedly uniting said slat members adjacent to their relatively adjoining longitudinal edges; and roller means carried at the ends of said slat members and received in certain of the guideways of said end members and brackets, the hinged connecting means of said slat members providing for transverse flexing of the bed formed thereby in enabling said bed to fold upon itself while positioned in the upper, lower and arcuate portions of the guideways provided in the bracket extensions.

2. A portable carrier as defined in claim 1 and 75 wherein the connecting means uniting said slat

members embody a plurality of plate sections rigidly secured to the ends of said slat members, said plate sections being formed with interfitting pintle-receiving hinge sleeves at their ends and with integral depending ears upon which said roller means are mounted, and pintles positioned in said sleeves.
